ALEXANDRE BARBIER, OF LYON, FRANCE.

SHUTTLE-BOX MOTION FOR LOOMS.

Application filed August 27, 1925, Serial No. 52,757; and in France December 5, 1924.

This invention relates to shuttle box motions of looms of the kind in which toothed sectors carried by a rotatably mounted plate or disc are adapted to engage with freely rotatable satellite pinions, whereby each pinion is periodically given a half rotation at each passage of a toothed sector in engagement therewith, the pinions being adapted to be respectively clutched, under the control of the card mechanism of the loom, to corresponding rotatable members mounted upon the same axes as the satellite pinions and provided with cranks or crank pins by which movement of the rotatable members is communicated to the shuttle boxes through lever mechanism, one half rotation of the respective pinions serving to effect the rise of the shuttle boxes, while the succeeding half rotation serves to effect the fall of the boxes. By suitable operation of the clutches by which the satellite pinions are connected to the respective rotatable members, any desired position of the shuttle boxes may be obtained.

The invention specially relates to shuttle box looms of the kind referred to, such as described in the specification of the co-pending application No. 16,459 dated 18th March, 1925, Patent No. 1,617,143, and in which four satellite pinions disposed two and two in different planes are employed, whereby any desired position of the shuttle boxes from one to twelve may be obtained, the rotatable members being connected to the shuttle boxes by means of lever and rack and pinion mechanism so arranged that a half rotation of each of two of the satellite pinions causes the shuttle boxes to rise or fall to an extent of four boxes, while the third and fourth satellite pinions cause the rise or fall of the boxes to an extent of two boxes and one box respectively.

In such mechanism each satellite pinion is clutched to the respective rotatable member by means of a pin mounted within a hole in the rotatable member or a part integrally secured thereto, which pin is adapted alternatively to engage within one of two diametrically disposed holes in the satellite pinion, the pin being pressed into the respective hole by means of an operating member under the control of the card mechanism.

The present invention has among its objects to provide an improved construction of the mechanism by which the clutching

of the satellite pinions to the respective rotatable members is effected.

According to the present invention in shuttle box motions of the kind referred to the means by which each satellite pinion is alternatively clutched under the control of the card mechanism of the loom to the respective rotatable member, comprises a pin mounted to revolve with and about the axis of the rotatable member, and adapted to engage alternatively with one of two corresponding diametrically disposed holes in the satellite pinion, a pair of independent operating members disposed laterally of the axis of the satellite pinion in determined positions, such that they may operate to press the pin into one of the two diametrically disposed holes in the satellite pinion, whereby one operating member serves to effect the rise of the shuttle boxes and the other to effect the fall of the shuttle boxes, and means connecting each of the said operating members to the card mechanism of the loom.

The invention is hereinafter described by way of example with reference to the accompanying diagrammatic drawing, in which:

Fig. 1 is a front sectional elevation on the line E—F Figure 2 showing one of the four satellite pinions.

Fig. 2 is a horizontal section on the line A—B, Figure 1.

Fig. 3 is a sectional side elevation on the line C—D Figure 2, and

Fig. 4 is a rear view corresponding to Figure 1.

The pinion *a* is provided freely rotatable and with two diametrically disposed holes *c* in which holes a pin *d* carried in a part *f*, keyed or otherwise integrally secured to a sleeve or member *n* rotatably mounted upon the spindle or shaft *b*, may alternatively be engaged. The pin *d* is provided with a return spring *e* mounted within a recess provided for the purpose within the part *f*. The parts *f*, *g* and *h* form an integral unit which is rotatable upon the spindle or shaft *b* and is maintained in position on the spindle or shaft *b* by means of the ring *g* and the disc *h* and at its forward extremity by the flange *m* on the spindle or shaft *b* engaging within corresponding recesses in the sleeve or member *n*. The sleeve or member *n* is at its outer extremity provided with a laterally extending flange or part *n*' upon

the face of which a crank n^2 or the equivalent, by which motion is transmitted to the shuttle boxes, is mounted. The pinion a is rotatably mounted upon the sleeve and is disposed between the laterally extending flange or part n^1 of the sleeve or member n and the part f . The pinion a is rotated intermittently, but always in the same direction and through half a revolution on each movement. It will be understood that, the crank n^2 being disposed, for example, in the uppermost position, the pin d is disposed, for example, at 90° to one side. If the pin be engaged with the pinion a in one of the holes c, c^1 , the pinion will carry the crank n^2 into the lowermost position thus raising the shuttle boxes or vice versa. The pin d will now be disposed in the opposite lateral position and when it is next engaged with the pinion a the latter will carry the crank n^2 again to the uppermost position thus lowering the shuttle boxes or vice versa.

Two operating arms i, j are pivotally mounted upon the spindle k , and are integrally provided with the respective arms i^1, j^1 respectively forming bell crank levers, and the respective arms i^1, j^1 are each connected at their ends to flexible members or cables l actuated by the card mechanism of the loom.

When for example the upward movement of the boxes to dispose a particular box in the working position is to be effected the flexible member or cable l connected to the arm i^1 is pulled whereby the operating arm i forces the pin d into engagement with the hole c^1 in the pinion a , so that the latter is thus clutched to the rotatable sleeve or member n .

A spring pressed pin e mounted within a recess in a stationary part of the mechanism is adapted to press against the rear face of the disc h and thus to exercise a slight retarding effect on the rotatable sleeve or member n . By such means while the pinion is being rotated the pin d engaging within the hole c^1 in the pinion a is subjected to a slight shearing action sufficient to maintain it within the hole c^1 until the rotation of the pinion ceases whereupon the pin d is withdrawn from the hole c^1 by means of the spring e . By such means the half rotation of the pinion is transmitted to the rotatable sleeve or member n and the shuttle boxes are caused to move into the desired position.

When the fall of the boxes is to be effected, the operating arm i^1 having been allowed to return to the inoperative position so that the pinion a turns freely, the arm j^1 is actuated by the respective flexible member or cable l to force the pin d again into the hole c^1 in the pinion a causing the descent of the boxes.

I claim:—

1. In a shuttle box motion of the type

comprising a rotatable part, toothed sectors carried by said rotatable part, freely rotatable satellite pinions adapted to engage with said toothed sectors and to be rotated thereby through half a revolution at each passage of the toothed sectors in engagement therewith, rotatable members mounted co-axially with the respective satellite pinions, and mechanism connecting the said rotatable members to the shuttle boxes whereby one half revolution of a rotatable member causes the shuttle boxes to rise, while the succeeding half rotation causes the shuttle boxes to fall, the provision of means by which each satellite pinion is alternatively clutched under the control of the card mechanism of the loom to the respective rotatable member, the said means comprising two diametrically disposed holes in the respective satellite pinion, a pin mounted to revolve with the respective rotatable member and about the axis thereof and adapted to engage alternatively with one of the two diametrically disposed holes in the respective satellite pinion, and a pair of independent operating members disposed laterally of the axis of the satellite pinion in determined position such that they may operate to press the pin into either of the two diametrically disposed holes in the respective pinion whereby one operating member serves to effect the rise of the shuttle boxes and the other to effect the fall thereof, and means connecting each of said operating members to the card mechanism of the loom, substantially as described.

2. In a shuttle box motion of the type comprising a rotatable part, toothed sectors carried by said rotatable part, freely rotatable satellite pinions adapted to engage with said toothed sectors and to be rotated thereby through half a revolution at each passage of the toothed sectors in engagement therewith, rotatable members mounted co-axially with the respective satellite pinions, and mechanism connecting the said rotatable members to the shuttle boxes whereby one half revolution of a rotatable member causes the shuttle boxes to rise, while the succeeding half rotation causes the shuttle boxes to fall, the provision of means by which each satellite pinion is alternatively clutch under the control of the card mechanism of the loom to the respective rotatable member, the said means comprising two diametrically disposed holes in the respective satellite pinion, a pin mounted to revolve with the respective rotatable member and about the axis thereof and adapted to engage alternatively with one of the two diametrically disposed holes in the respective satellite pinion, and a pair of independent bell crank levers disposed laterally of the axis of the satellite pinion in determined position such that they may operate to press the pin into either of the

- two diametrically disposed holes in the respective pinion whereby one bell crank lever serves to effect the rise of the shuttle boxes and the other to effect the fall thereof, and 5 means connecting each of said bell crank levers to the card mechanism of the loom, substantially as described.
3. In a shuttle box motion of the type comprising a rotatable part, toothed sectors 10 carried by said rotatable part, freely rotatable satellite pinions adapted to engage with said toothed sectors and to be rotated thereby through half a revolution at each passage of the toothed sectors in engagement there- 15 with, rotatable members mounted co-axially with the respective satellite pinions, and mechanism connecting the said rotatable members to the shuttle boxes whereby one half revolution of a rotatable member causes 20 the shuttle boxes to rise, while the succeeding half rotation causes the shuttle boxes to fall, the provision of means by which each satellite pinion is alternatively clutched under the control of the card mechanism of 25 the loom to the respective rotatable member, the said means comprising two diametrically disposed holes in the respective satellite pinion, a pin mounted to revolve with the respective rotatable member and about the 30 axis thereof and adapted to engage alternatively with one of the two diametrically disposed holes in the respective satellite pinion, and a pair of independent operating members disposed laterally of the axis of 35 the satellite pinion in determined position such that they may operate to press the pin into either of the two diametrically disposed holes in the respective pinion whereby one operating member serves to effect the rise of 40 the shuttle boxes and the other to effect the fall thereof, and a flexible member such as a cable connecting each of said operating
- members to the card mechanism of the loom, substantially as described.
4. In a shuttle box motion of the type 45 comprising a rotatable part, toothed sectors carried by said rotatable part, freely rotatable satellite pinions adapted to engage with said toothed sectors and to be rotated thereby through half a revolution at each passage 50 of the toothed sectors in engagement therewith, rotatable members mounted co-axially with the respective satellite pinions, and mechanism connecting the said rotatable members to the shuttle boxes whereby one 55 half revolution of a rotatable member causes the shuttle boxes to rise, while the succeeding half rotation causes the shuttle boxes to fall, the provision of means by which each satellite pinion is alternatively clutched under the control of the card mechanism of the 60 loom to the respective rotatable member, the said means comprising two diametrically disposed holes in the respective satellite pinion, a pin mounted to revolve with the respective rotatable member and about the axis thereof and adapted to engage alternatively with one of the two diametrically disposed holes in the respective satellite pinion, 65 spring means serving to withdraw the pin from the respective holes in the satellite pinions, and a pair of independent operating members disposed laterally of the axis of the satellite pinion in determined position such that they may operate to press the pin into either of the two diametrically disposed holes in the respective pinion whereby one operating member serves to effect the rise of the shuttle boxes and the other to effect the fall thereof, and means connecting each 70 of said operating members to the card mechanism of the loom, substantially as described.

ALEXANDRE BARBIER.
